WATER PISTOL

Irwin Cohn, Leominster, Mass.

Application October 24, 1956, Serial No. 618,021

14 Claims. (Cl. 222—79)

My invention relates to toy pistols and is directed particularly to a water pistol or toy pistol operative to eject a stream of water or like liquid when the trigger is actuated.

Water pistols have heretofore been constructed in many different ways. Prior constructions, however, because of using check valves, closed pump cylinders, two-part molded water channels and pump cylinders, and other comparatively complicated and troublesome water-ejecting mechanisms, are difficult to assemble and relatively inexpensive to manufacture.

It is accordingly the principal object of my invention to provide an improved toy water pistol which utilizes a minimum of parts, which has no molded water channels, no two part molded pump cylinder, no check valves, and which does not require a closed pump cylinder.

It is another object of my invention to provide a water pistol of the character described in which the body can readily be molded in two parts of synthetic plastic material, the parting line being transverse to the longitudinal axis of the pistol barrel and extending substantially centrally through the pistol grip, thereby providing a completely unsplit, truer, open pump cylinder.

A still further object of this invention is to provide in a water pistol of the character described, a flexible tube extending from the muzzle to substantially the bottom of the pistol grip, thereby eliminating the necessity for a molded water channel, and permitting ejection of practically all of the water in the pistol.

Yet another object of this invention is to provide in a water pistol of the character described, a highly improved metal gun nozzle attached to the front end of a flexible tube and held in place by a disc at the front end of the muzzle of the gun.

Still another object of my invention is to provide a highly improved water pistol of the above nature, the parts of which are inexpensive to manufacture and easy to assemble, and which is compact, attractive in appearance, foolproof in operation, and durable in use.

Further objects, features and advantages of my invention will become apparent from the following description when read with reference to the drawings.

In the drawings, wherein like reference numerals denote corresponding parts in both views,

Fig. 1 is a longitudinal cross-sectional view of a water pistol embodying the invention;

Fig. 2 is a cross-sectional view taken on line 2—2 of Fig. 1;

Fig. 3 is a cross-sectional view taken on line 3—3 of Fig. 1;

Fig. 4 is a cross-sectional view taken on line 4—4 of Fig. 1;

Fig. 5 is a vertical cross-sectional view illustrating a modified construction of the muzzle of the gun; and

Fig. 6 is a view similar to Fig. 5 and illustrating another modification.

Referring now to the drawings, numeral 10 designates generally a preferred embodiment of the improved water

2

pistol comprising the invention. The water pistol 10 has its body formed of hollow front and rear shell members 12 and 14, respectively, which in assembled relation are cemented together at their open ends on a parting line 5 indicated by reference numeral 16. Thus the rear edge of the front portion 12 abuts and is adhered to the front edge of rear portion 14. The front shell member 12 is formed with a "barrel" portion 18 simulating the barrel of a real pistol. The front and rear shell members 12 and 10 14 when in assembled relation form a downwardly extending "grip" portion 20 simulating the hand grip of a real pistol. The upper end of the rear shell member 14 is located back of barrel 18. Molded within the front shell member 12, below the barrel portion 18 thereof, 15 is an open-ended pump cylinder 22 the front wall 23 of which comprises part of the front wall of shell 12 and is provided with an opening 24. Slidably disposed in the cylinder 22 is a cylindrical piston 26 of flexible material, 20 preferably molded of polyethylene and formed with an outwardly and rearwardly extending outwardly flaring peripheral lip 28 which resiliently and wipingly engages about the interior surface of the pump cylinder 22. The piston 26 is formed at its forward end with a central circular rearward depression 30 within which is secured in 25 any suitable manner, through the opening 24, the rearwardly-extending actuating arm 32 of a "trigger" member 34. The upper end of trigger member 34 is slidably disposed and guided for front to back motion in a channel 36 provided by a pair of spaced parallel guide 30 rails 38 molded underneath the barrel portion 18 of the front shell member 12.

A cylindrical boss 40 is molded within the rear shell member 14, said boss being so disposed as to lie in axial alignment with the pump cylinder 22 when the front and 35 rear shell members 12 and 14 are in assembled relation. A compression coil spring 42 is constrained between and fitted on the boss 40 and the annular seat defined in the rear end of the piston 26 by the circular depression 30 thereof. The compression spring 42 is operative to normally hold the piston 26 against the end wall 23 of the piston cylinder 22 and thus urge the trigger 34 into its forwardmost position.

The muzzle end 43 of the barrel portion 18 of the front shell member 12 is formed or provided with an interior 45 annular wall portion 44 having a rearwardly-extending central cylindrical opening 46 of reduced diameter communicating with a forwardly-extending small diameter nozzle aperture 48. Fitted and sealed, in any suitable manner in the reduced diameter opening 46 is one end 50 of a flexible length of tubing 50, preferably of a synthetic plastic material or rubber, the other end of said length of tubing being bent downwardly to extend almost to the bottom of the lower chamber within the grip portion 20 of the pistol body. The lower end 51 of the tubing 50 is angled so that opening 46 cannot "close up" by contact with the lower end of the hand grip.

The upper end of the rear wall of the rear shell member 14 of the pistol body is provided with a water charging opening 52 which can be tightly sealed by plug 60 after charging the pistol with water W.

In operation, squeezing of the trigger 34 pushes the piston rearwardly in its cylinder 22 against the compressional force of the spring 42, reducing the total volume of the interior of the pistol and thereby forcing water W through the tubing 50 and ejecting it out of the nozzle aperture 48 under pressure. Upon release of the trigger 34, the compression spring 42 will again move the piston 26 against the front wall 23 of the cylinder, during which movement air will enter the pistol through the tube 50 into the pistol interior to replace the volume of water ejected by the preceding actuation of the trigger.

In Fig. 5 there is shown a modified construction of

the muzzle of the gun. In said figure, the muzzle 18a corresponding to the muzzle 18 of Fig. 1, has fixed in the front end thereof a disc 70 formed with a central opening 70a. Inserted into said opening 70a and fixed therein is a metal nozzle member 71. Said nozzle member 71 has a rearwardly tapering wall 72 and a front wall 73. The front wall 73 is formed with a central opening 75 and has an inner conical wall 74. The inner surface of wall 72 is cylindrical but the outer surface thereof decreases towards the rear. Inserted into the socket formed by member 71 and contacting the inner surface of the wall 72 is the front end of tube 50a which is otherwise similar to tube 50 of Fig. 1. The tube 50a may be adhered to the nozzle 71 in any suitable manner and disc 70 may be cemented or otherwise adhered in place in any suitable manner.

In Fig. 6 there is shown another modification, similar to Figs. 1 and 5, except that the front end 43b of the muzzle 18b is provided with an integrally molded transverse wall 70b. Said wall 70b is formed with a central opening 70c, receiving a metal nozzle member 71a. The latter has a wall 80 extending through the opening 70c, a front wall 81 formed with a central pin opening 82, and a rear outwardly extending annular flange contacting wall 70b. The front end of flexible tube 50a is fixed within the nozzle member 71a.

While I have described a preferred embodiment of my invention, it is to be understood that this disclosure is for the purpose of illustration only and that various omissions, or changes in arrangement of parts, as well as the substitution of equivalent elements for those herein shown and described may be made without departing from the spirit and scope of the invention as set forth in the appended claims.

What I claim as new and desire to secure by Letters Patent is:

1. A water pistol provided with barrel, muzzle and hand grip portions, and comprising front and rear hollow members attached together along a plane transverse to the barrel portion, a pump cylinder integrally formed with said front member and extending rearwardly, a piston in said cylinder, a trigger slidably mounted on said front member and attached to said piston, and a tube connected at one end to said muzzle portion and projecting down into the hand grip portion.

2. The combination of claim 1, and a spring interposed between the piston and the rear hollow member.

3. The combination of claim 1, a portion of said front hollow member forming the front end of said cylinder, the front end of said cylinder being formed with an opening, and said trigger comprising a stem passing through said opening for engagement with said piston.

4. The combination of claim 3, and a spring interposed between said piston and said rear hollow member.

5. A water pistol comprising a barrel portion, a muzzle portion and a hand grip portion, said pistol being hollow, a cylinder integrally formed with said pistol and extending rearwardly from a front wall thereof and being open at its rear end, said front wall being formed with an opening, a trigger having a stem passing through said opening, a piston within said cylinder having a recessed portion receiving said stem, and a tube fixed at one end to said muzzle and being disposed within said pistol and having its other end disposed adjacent the bottom of the hand grip.

6. A water pistol comprising a hollow body having a barrel simulating portion, a muzzle simulating portion and a hand grip simulating portion, a cylinder integrally formed with the body and disposed within the hand grip

portion and extending rearwardly from the front of said hand grip portion and being opened at its rear end, a piston within said cylinder, the front of said hand grip position being formed with an opening, and a trigger slidably mounted on said body and extending through said opening and engaging said piston.

7. The combination of claim 6, and a tube attached at one end to the muzzle and having its other end located within the hand grip portion.

8. The combination of claim 7, and a spring interposed between the piston and the rear wall of said hand grip portion.

9. The combination of claim 7, said piston and rear wall having bosses and a coil compression spring disposed between said piston and rear wall and receiving said bosses.

10. A water pistol comprising a hollow body having a muzzle, a transverse disc portion within said muzzle and formed with a central opening, a nozzle inserted into said opening in the disc, a flexible tube having one end received in said nozzle, and means to pump liquid through said tube, said nozzle having a front wall formed with a central opening, and an annular wall passing through said opening, and a rear flange contacting the rear of said disc portion.

11. A water pistol comprising a hollow body having a muzzle, a transverse disc portion within said muzzle and formed with a central opening, a nozzle inserted into said opening in the disc, a flexible tube having one end

30 received in said nozzle, and pump means to pump liquid through said tube, said pump means comprising a cylinder integrally formed with the body and disposed therein and having a rear open end, a piston in the cylinder having wiping engagement therewith, a spring interposed between the piston and the rear wall of the body, and trigger means for moving said piston, said body having an opening, said trigger means including a stem passing through said opening in the body, said piston having a recess receiving said stem.

40 12. The combination of claim 11, said body comprising a front hollow body portion and a rear hollow body portion, the rear edge of the front body portion abutting and being attached to the front of the rear body portion.

13. The combination of claim 1, said cylinder being 45 opened at its rear end.

14. A water pistol comprising a front hollow member and a rear hollow member, the rear edge of the front member abutting and being adhered to the front mating edge of the rear member along a transverse plane, said 50 pistol having a muzzle, a handle grip portion, a flexible imperforate tube attached at one open end to said muzzle and having its other open end extending downwardly into the bottom of said hand grip portion and pump means for ejecting water through the tube to the muzzle of the water pistol, the lower open end of said tube extending below said pump means, said pump means comprising a cylinder integrally formed with said front hollow member and extending rearwardly, a piston within said cylinder, said front hollow member having an opening and a trigger slidably mounted on said front hollow member and passing through said opening and engaging said piston.
